UNITED STATES PATENT OFFICE.

HENRY BREHMER, OF STAPLETON, ASSIGNOR TO DAVID WOLFE BRUCE,
OF NEW YORK, N. Y.

DESIGN FOR TYPE.

SPECIFICATION forming part of Design No. 16,067, dated May 5, 1885.

Application filed December 13, 1884. Term of patent 14 years.

To all whom it may concern:

Be it known that I, HENRY BREHMER, (assignor to DAVID WOLFE BRUCE,) of Stapleton, county of Richmond, and State of New York, have invented a Design for a Font of Printing-Type, of which the following is a specification.

The nature of my design is clearly shown in the accompanying typographic impression, to which reference is made; and it consists of an ornamental letter somewhat resembling the dress known as "Tuscan," shaded on the right and below by a lighter line following the configuration of the letter, which shading is connected to the letter proper by the short lines, as shown upon the right at the top of the letter and at the bottom upon the left of the letter.

The curved line with heavy dot termination is found in the A, B, C, E, F, G, J, K, L, R, S, T, Z, and symbol &, as shown. The upper termination upon the right of the C, E, F, G, S, and J is concaved, as shown, and this feature is found in the lower termination upon the right of the E, L, and Z, and in the upper termination upon the left of the T and Z.

The character of the design is preserved in the punctuation-marks, the numerals, and the dollar and pound-sterling marks.

My design also shows the A extended below the line upon the left, and the K and R extended below the line upon the right.

It differs from the design on page 124 of Bruce's specimen book, Letters Patent No. 12,263, as follows: This letter resembles closely the class known as "mediaeval." The shade-line upon the right and bottom is separate and disconnected from the letter proper. The cross-lines of the A, B, and H are not curved as in the present case. None of the letters extend below the line. The cross-ornamentations of the E and F are not formed as in the present case, particularly in the F, which shows the curved line with heavy dot termination at its base. The M, N, U, V, and W in that example are essentially different from the same letters in the present case. There is no concaving of the terminations of the letters, as heretofore referred to in this case.

Having now described my invention, I claim as new—

The design for a font of printing-type, consisting of an ornamental letter shaded upon the right and below by a lighter line connected to the letter, as shown, and said letter being provided with a curved termination followed by a heavy dot, and concaved as shown, and the A, K, and R being extended below the line, as described.

HENRY BREHMER.

In presence of—

W. V. H. HICKS,
A. SIDNEY DOANE.
